FIG. 1 is a front perspective view of the container according to this invention showing our new design therefor;
 FIG. 2 is a front elevation of the container, the rear elevation is a mirror image thereto except for the conventional screw threading on the neck;
 FIG. 3 is a left side elevation of the container shown in FIG. 1;

FIG. 4 is a top view of the container shown in FIG. 1; and,
 FIG. 5 is a bottom view of the container shown in FIG. 1. The portions of the right side of the container that are not shown in the drawings do not form part of the claimed design.

The broken line showing of another container body portion in the accompanying figures is for illustrative environmental purposes only and forms no part of our claimed design.
